UNITED STATES PATENT OFFICE.

ALFRED J. SCHULZ AND HERBERT H. SCHULZ, OF MILWAUKEE, WISCONSIN.

DOORSTOP ACTUATOR.

Application filed February 7, 1924. Serial No. 691,112.

This invention relates to improvements in door stops.

There is a type of door stop, (one embodiment of which is disclosed in the co-pending application of Richard H. Buerger and Alfred J. Schulz, Serial No. 577,508, filed July 26, 1922), which includes a member pivoted to the door and adapted for movement between an elevated inactive position and an operative position, in which the door stop is disposed at an angle to the door to brace the door against closing movements. It is the primary object of this invention to provide a simple unobtrusive modification for the type of door stops aforesaid, whereby such a door stop can be operated with the foot instead of requiring manual manipulation. It is particularly desired that the actuating device shall be such as to have a limited movement. It will be understood that if the actuator were made fast to the door stop the stop would either have to be pivoted to the door at some distance therefrom or the projecting, foot-engaged portion of the actuator would impede the movement of the door stop by encountering the door during the downward movement of the stop. It is a further object of this invention, therefore, to provide a device in which the actuator has a limited movement, only sufficient to impel the door stop proper toward its operative position.

In the drawings:

Figure 1 is a side elevation of one embodiment of this invention.

Figure 2 is a front elevation of the device shown in Figure 1.

Figure 3 is a section taken on line 3-3 of Figure 2.

Figure 4 is a side elevation of a modified construction embodying this invention.

Figure 5 is a front elevation of the device shown in Figure 4.

Figure 6 is a side elevation of a further modified construction.

Figure 7 is a front elevation of the device shown in Figure 6.

Figure 8 is a detail view in plan of the actuator shown in Figures 6 and 7.

Figure 9 is a front elevation of a device similar to the device shown in Figures 6 and 7 but illustrating a different mounting for the actuator.

Figure 10 is a side elevation of a further modified embodiment of this invention. 55

Figure 11 is a front elevation of the device shown in Figure 10.

Figure 12 is a detail view on an enlarged scale, showing in perspective a fragmentary portion of the device illustrated in Figures 10 and 11. 60

Like parts are identified by the same reference characters throughout the several views.

While the door stop is of the construction more particularly disclosed in the companion application above referred to, it will be understood that this invention may be applied to other door stops operating upon similar principles. 65

The door stop mounting includes a pair of spaced flanged plates 15 and 16, the flanges of said plates being designated respectively by reference characters 17 and 18. Suitable screws or nails 19 will be passed through the apertures of the plates to secure them in properly spaced relationship upon the inner face of a door, shown at 20 in Figures 1 and 3. In view of the fact that device of this general character are well known it has not 80 been thought necessary to disclose the mounting of the device other than in the two views aforesaid. 70

The door stop proper comprises a rod 25 formed at one end with an eye 26. A transverse bolt or pin 27 passes through plates 15 and 16 and through the eye 26 of the door stop 25, whereby to secure the stop in pivoted relation to door 20. It will be understood that when the door stop is lowered 90 to the operative position, in which it is shown in broken lines in Figure 1, it will engage the floor or the ground beneath the door and act as a brace to prevent the door from moving in one direction. 95

When it is desired to retain the door stop 25 in an inoperative position the stop is moved upwardly about pivot pin 27 to the positions indicated in full lines in Figures 1 and 2. The plate 16 is provided with a 100 protuberance 29 behind which rod 25 will be engaged in the manner clearly indicated in Figures 1, 2, and 3. It will be understood that the plate 16 is sufficiently resilient to spring outwardly to permit the passage of 105 rod 25. Preferably the arrangement is such

- that the rod will contact at its free end with the face of the door before plate 16 and protuberance 29 have been resiliently restored entirely to their normal positions.
- 5 Thereby, the door stop will be retained quite rigidly in its inoperative position and will not have such freedom of movement to the rear of protuberance 29 as would permit it to rattle.
- 10 The protuberance 29, while it is desirable for the purpose of overcoming any tendency to rattle and for the purpose of retaining door stop 25 firmly in place against momentum effects produced by sudden door movements, is not absolutely necessary to retain the door stop in its elevated position, inasmuch as the door stop, as indicated in the drawings, is obviously movable beyond a balanced position about pivot pin 27 so
- 15 that gravity tends to maintain the door stop in contact with the face of the door in the manner shown in Figure 1. It is very desirable, however, to make a device of this kind as inconspicuous as possible and it is, therefore, considered an advantage to have plates 15 and 16 of relatively small horizontal dimensions and to keep the pivot pin 27 fairly close to the face of the door. Thus, the angle of rod 25 beyond the vertical is
- 20 not considerable and the function of the button or protuberance 29 is more significant than might otherwise be assumed. Obviously, however, the operation of the actuating device hereinafter to be described will be unaffected by the question as to whether the door stop is maintained in its inoperative position wholly by the force of gravity or by some retaining feature, such as the protuberance 29.
- 25 All of the different constructions of actuator herein disclosed are comparatively simply and cheaply constructed. Each of them is entirely automatic in its action, in the sense that it is restored to a position for subsequent operation by the movement of the door stop toward its inoperative position.
- 30 The actuator shown in Figures 1 to 3, inclusive, is positioned immediately adjacent plate 15 and exterior thereto. It
- 35 comprises a lever which is generally of L-shape, having an arm 30 which normally projects horizontally and an arm 31 which normally projects substantially vertically. The arm 30 will preferably have a laterally
- 40 bent flange 33 comprising a pedal, and arm 31 will carry at its end a transversely extending finger 35 adapted for engagement behind rod 25. The entire device is mounted as a bell crank upon the pivot pin 27, or upon some other convenient fulcrum.
- 45 The arrangement is such that when the rod 25 is moved upwardly to its inoperative position, as shown in full lines in Figures 1 and 2, it will carry with it the bell crank, including arms 30 and 31, and will retain
- 50 behind it finger 35. When the operator desires to release the door stop from its inoperative position behind protuberance 29 it will be necessary only for him to depress pedal 33, whereby the bell crank actuator will pivot upon pin 27 carrying with it, through the engagement of finger 35 upon rod 25, the door stop.
- 55 It is preferred that the movement of the actuator shall be limited. The movement should, of course, be sufficient to impel the door stop past the protuberance 29 and past the dead center position of the door stop above its pivotal axis. Thereafter, the door stop will fall, by its own weight, about pivot 27 to contact with the ground, where it will remain in operative position until restored manually or by the foot of the operator. It is not necessary, however, for the actuator to move a great distance in order to accomplish this result. In order that the door stop may not project in an objectionable manner from the door, it is preferred that the actuating device be restricted in its movement so that it will not swing materially beyond the point in which it is illustrated in broken lines in Figure 1. The bell crank is, therefore, preferably provided with a shoulder portion 36 adapted to abut flange 17 and thereby to limit actuator movement.
- 60 The actuator shown in Figures 4 and 5 has substantially the same mode of operation as that already disclosed. It is, however, provided with an independent fulcrum of its own, and instead of being made from sheet metal it may be made from a round bar or the like.
- 65 Where the device shown in Figures 4 and 5 is to be used, the plates 15 and 16 will be provided with registering apertures spaced slightly above the apertures which receive pivot pin 27 for rod 25. The actuator may comprise simply a piece of round bar material bent to form integrally a bell crank device somewhat similar to that disclosed above. The portions 38 and 39 of the bar are substantially in alignment and find a bearing in the apertures of plates 15 and 16. Intermediate these bearing portions 38 and 39 the bar is bent, as indicated in Figure 5, to provide an upwardly projecting tongue 40 adapted for engagement at the rear of rod 25. From one of the bearing portions 38 or 39 the bar is bent to provide a pedal portion 41 which normally extends forwardly for engagement by the foot of the operator. The arrangement is such that when the door stop rod 25 is in its elevated position, tongue 40 of the integrally bent bar comprising the actuator will be engaged behind rod 25, as illustrated, and the pedal portion 41 of the bar will be substantially horizontal. When the operator
- 70 presses downwardly upon the pedal portion

- 130

41 the bar oscillates upon the axis of its bearing portions 38 and 39, thereby causing tongue portion 40 to contact with rod 25 and impel said rod forwardly beyond its balanced position above the fulcrum pin 27.

10 In Figures 6, 7, and 8 a device is disclosed which corresponds quite closely to the device shown in Figures 1, 2, and 3, with the exception that it is formed to engage door stop rod 25 much closer to the axis of said rod.

15 In the construction illustrated in Figures 6, 7, and 8 the arm 30' and pedal 33' correspond closely to the arm 30 and pedal 33 of the device shown in Figures 1 to 3. Similarly, the arm 31' and finger 35' correspond to the parts 31 and 35 of above mentioned disclosure. The length of arm 31', however, is considerably less than the length 20 of arm 31, and in order to permit finger 35' to engage rod 25 an arcuate slot 43 is provided in the wall of plate 15. The extent of this slot will also limit the arcuate movement of finger 35' and will thereby limit the extent of oscillation of the actuator. No shoulder corresponding to shoulder 36 is necessary in the construction shown in Figures 6 to 8, 25 inclusive.

30 It is particularly to be noted that the devices shown in Figures 1 to 3 and Figures 6 to 8 may be mounted either internally or externally of plates 15 and 16. In Figure 9 we have illustrated the last described actuator fulcrumed upon pivot pin 27 between 35 plates 15 and 16 and immediately adjacent rod 25 instead of externally of plate 15, as disclosed in Figure 7.

35 In the construction illustrated in Figures 10 and 11 the door stop proper may conveniently comprise a strip of channel iron 25' mounted and arranged to correspond in function and operation to the rod 25. The flanged plates 15 and 16 may be identical with those already described. In place of 40 bolts 27, however, we provide a pin 27' having a squared end 45 upon which is mounted a lever 46. The lever 46 has a pedal portion 47 and a shoulder 48 arranged to abut the flange 17 of plate 15 and thereby to limit the 45 oscillatory movement of the shaft section 27'.

50 The shaft section extends not only through plates 15 and 16 but also through registering apertures 49 and 50 in the flanges 51 and 52, respectively, of the channel iron door stop member 25'. The arrangement is such that the door stop member can oscillate freely about shaft section 27'.

55 Suitably positioned to project radially and downwardly from a central portion of shaft section 27' is a short arm which may take the form of a pin 53, and which is of sufficient length to contact with the central or web portion 54 of the channel iron door stop 25'. The arrangement is such that when the 60 pedal 47 on lever 46 is depressed the shaft 55

section 27' will receive oscillatory motion through its squared end 45, and will thereby be caused to rock clockwise (as viewed in Figure 12) to the extent permitted by shoulder 48. In the course of such rotation, pin 76 53, through its contact with web portion 54 of the channel iron brace member 25', will cause the brace member to oscillate past its neutral position above shaft section 27', whereby said brace member will fall by 75 gravity into operative position.

It will appear from the foregoing that there are a variety of possible constructions which may be utilized to satisfy in general the broader objects of this invention. In 80 each case a door stop of the type hereinbefore specified is provided with an actuator which preferably has a limited movement and is restored automatically to operative position by the final movement of the door stop to its inactive position. In each case the arrangement is such that the entire contrivance can readily be manipulated by the foot of the operator, the actuator pedal being so disposed with reference to the plane of 85 movement of the door stop that there is no necessity for the operator's foot interfering with the movement of the stop. Furthermore, due to the fact that the limit of movement of the actuator is preferably limited, 90 there will be nothing to interfere with the free movement of the door stop or brace member in the several positions which such member may assume when operative.

95 We claim:

100 1. A door stop device oscillatory in a substantially vertical plane through a balanced position above its pivot, in combination with an actuating device operatively disposed with reference to said door stop for the propulsion thereof through said position, said device being normally disconnected from said stop.

105 2. In a device of the character described, the combination with a brace member oscillatory in a substantially vertical plane, of an oscillatory actuator having a portion engageable with said brace member for the propulsion thereof, and having another portion adapted for pedal contact, said actuator being normally disconnected from said member.

110 3. In a device of the character described, the combination with a brace member pivoted for unobstructed movement in a substantially vertical plane, of an independently oscillatory actuator including a portion engageable at one side of said member for the propulsion thereof in one direction, a pedal portion, and means for limiting the movement of said actuator in one direction while permitting continued movement of said member in said direction.

115 4. In a device of the character described, the combination with a support and a brace 120

125

130

member pivoted for movement with respect thereto, of an actuator pivoted for independent movement with respect to said support and including a bell crank having two divergent arms, one of said arms being provided with a finger engageable behind said member.

5. In a device of the character described, the combination with a bracket providing a fulcrum, of a brace member oscillatory thereon, and an actuator engageable with said brace member and fulcrumed for limited independent movement with respect to said bracket.

15 6. In a device of the character described, the combination with a bracket providing a fulcrum, of a brace member oscillatory thereon, an actuating device fulcrumed for independent oscillation with respect to said bracket, a finger carried by said device and engageable behind said member, and a stop means operative between said device and said bracket, whereby to limit the independent movement of said device.

25 7. In a device of the character described, the combination with a bracket providing a fulcrum, of a brace member oscillatory thereon between an operative position and an inactive elevated position, an actuator fulcrumed for independent movement with respect to said bracket, an arm carried by said actuator and engageable behind said member in the elevated position thereof, a pedal connected with said arm, and means 35 for limiting the oscillatory movement of said actuator.

8. In a device of the character described, the combination with a bracket and a brace member oscillatory with respect thereto, of a bell crank fulcrumed co-axially with respect to said member for relative independent movement and provided with an arm adapted for engagement with said member, and a pedal flange connected with said bell 45 crank and projecting laterally from the plane of movement of said member.

9. In a device of the character described, the combination with a bracket including a transversely extending fulcrum member, of a brace pivoted thereon for movement between an operative and an inactive position, a bell crank also pivoted thereon and provided with a normally horizontal arm, and a normally upright arm having a finger for engagement behind said brace, said bell 55 crank being movable independently of said brace and said first mentioned arm being laterally offset from the plane of movement of said brace, whereby to permit of the unobstructed movement of said brace between the positions aforesaid.

10. In a device of the character described, the combination with a bracket providing a transversely extending fulcrum member, a

brace pivoted upon said member for movement between operative and inactive positions, means for frictionally retaining said brace in its inactive position, and an independently movable actuator provided with a pedal portion and a portion engageable with said brace, said actuator being arranged for limited movement of adequate arcuate extent to relieve said brace from said frictional retaining means.

11. In a device of the character described, the combination with a bracket, of a brace member fulcrumed thereto for movement in an upright plane, and an actuator fulcrumed co-axially with said brace and movable independently thereof, said actuator being formed for interaction with said bracket, whereby its movement is limited.

12. In a device of the character described, the combination with a bracket, of a brace member fulcrumed thereto for movement in an upright plane and an actuator including means for engagement upon one side of said member, and pedal means projecting laterally from the plane of movement of said member, said actuator being fulcrumed to said bracket for movement independently of said member and being formed for interaction with said bracket, whereby to limit the degree of its movement.

13. In a device of the character described, the combination with a bracket including a pair of spaced plates, of a brace member fulcrumed between said plates, a fulcrum member extending transversely of said plates and providing a pivot for said brace member, and an actuator supported upon said fulcrum member externally of said plates and provided with a forwardly projecting arm and an upwardly projecting arm having a portion offset from said forwardly projecting arm and in the path of movement of said brace member, said offset portion being normally disengaged from said brace member.

14. In a device of the character described, the combination with a bracket including a pair of spaced plates, of a brace member fulcrumed between said plates, a fulcrum member extending transversely of said plates and providing a pivot for said brace member, and an actuator supported upon said fulcrum member externally of said plates and provided with a forwardly projecting arm and an upwardly projecting arm having a portion offset from said forwardly projecting arm and in the path of movement of said brace member, said actuator being formed for interaction with one of said plates, whereby to limit the extent of its oscillatory movement.
